FIG. 1 is a front perspective view of a wall-mounted modular honeycomb wine rack panel and portions, depicting a mounting orientation of the present invention.

U.S. PATENT DOCUMENTS

FIG. 2 is a front view of the wall-mounted modular honeycomb wine rack panel and portions of FIG. 1.

FIG. 3 is a rear view of the wall-mounted modular honeycomb wine rack panel and portions of FIG. 1.

FIG. 4 is a right-side view of the wall-mounted modular honeycomb wine rack panel and portions of FIG. 1.

FIG. 5 is a left-side view of the wall-mounted modular honeycomb wine rack panel and portions of FIG. 1.

FIG. 6 is a bottom view of the wall-mounted modular honeycomb wine rack panel and portions of FIG. 1.

FIG. 7 is a top view of the wall-mounted modular honeycomb wine rack panel and portions of FIG. 1.

FIG. 8 is a front perspective view of a portion of a wall-mounted modular honeycomb wine rack panel and portions, depicting another mounting orientation of the present invention.

FIG. 9 is a front view of the portion of the wall-mounted modular honeycomb wine rack panel and portions of FIG. 8.

FIG. 10 is a rear view of the portion of the wall-mounted modular honeycomb wine rack panel and portions of FIG. 8.

FIG. 11 is a right-side view of the portion of the wall-mounted modular honeycomb wine rack panel and portions of FIG. 8.

FIG. 12 is a left-side view of the portion of the wall-mounted modular honeycomb wine rack panel and portions of FIG. 8.

FIG. 13 is a bottom view of the portion of the wall-mounted modular honeycomb wine rack panel and portions of FIG. 8. FIG. 14 is a top view of the portion of the wall-mounted modular honeycomb wine rack panel and portions of FIG. 8. FIG. 15 is a front perspective view of a portion of a wall-mounted modular honeycomb wine rack panel and portions, depicting another mounting orientation of the present invention.

FIG. 16 is a front view of the portion of the wall-mounted modular honeycomb wine rack panel and portions of FIG. 15. FIG. 17 is a rear view of the portion of the wall-mounted modular honeycomb wine rack panel and portions of FIG. 15. FIG. 18 is a right-side view of the portion of the wall-mounted modular honeycomb wine rack panel and portions of FIG. 15. FIG. 19 is a left-side view of the portion of the wall-mounted modular honeycomb wine rack panel and portions of FIG. 15. FIG. 20 is a bottom view of the portion of the wall-mounted modular honeycomb wine rack panel and portions of FIG. 15. FIG. 21 is a top view of the portion of the wall-mounted modular honeycomb wine rack panel and portions of FIG. 15. FIG. 22 is a front perspective view of a portion of a wall-mounted modular honeycomb wine rack panel and portions, depicting another mounting orientation of the present invention.

FIG. 23 is a front view of the portion of the wall-mounted modular honeycomb wine rack panel and portions of FIG. 22. FIG. 24 is a rear view of the portion of the wall-mounted modular honeycomb wine rack panel and portions of FIG. 22. FIG. 25 is a right-side view of the portion of the wall-mounted modular honeycomb wine rack panel and portions of FIG. 22.

FIG. 26 is a left-side view of the portion of the wall-mounted modular honeycomb wine rack panel and portions of FIG. 22. FIG. 27 is a bottom view of the portion of the wall-mounted modular honeycomb wine rack panel and portions of FIG. 22. FIG. 28 is a top view of the portion of the wall-mounted modular honeycomb wine rack panel and portions FIG. 22. FIG. 29 is a front view depicting some of the many configurations that can be formed with two (2) units of a wall-mounted modular honeycomb wine rack panel and portions. FIG. 30 is a front view depicting some of the many configurations that can be formed with three (3) units of a wall-mounted modular honeycomb wine rack panel and portions. FIG. 31 is a front view depicting some of the many configurations that can be formed with four (4) units of a wall-mounted modular honeycomb wine rack panel and portions. FIG. 32 is a front perspective view of a configuration that can be formed with two (2) units of a wall-mounted modular honeycomb wine rack panel and portions.

FIG. 33 is a front perspective view of a configuration that can be formed with three (3) units of a wall-mounted modular honeycomb wine rack panel and portions; and, FIG. 34 is a front perspective view of a configuration that can be formed with six (6) units of a wall-mounted modular honeycomb wine rack panel and portions.

The broken lines shown in the figures represent portions of the wall-mounted modular honeycomb wine rack panel and portions that form no part of the claimed design.
